DENTAL TEMPLATE

Ross O. Dickson, Mexico City, Mexico

Application May 27, 1946, Serial No. 672,520

4 Claims. (Cl. 32—32)

1

This invention appertains to a dental template for use in setting up the teeth of artificial dentures and more particularly to a means for mounting the template on a standard type of dental articulator and in a manner to facilitate the accurate setting up of the teeth in conformity with the average occlusal curve of all sized individuals having either normal or abnormal natural denture formations.

Another object of the invention has to do with the provision of a dental template mounting as aforesaid and which is adapted for attachment to the jaw member of an articulator, for its easy and accurate adjustment thereon, by means of the usual model fixing lock-screw, without necessitating any modification of the articulator structure, or alteration in the usual arrangement of the parts thereof.

A further object of the invention lies in the provision of a dental template mounting of the kind specified and which is so constructed that it may be universally adjusted, raised or lowered, moved anteriorly or posteriorly, in order to establish any degree of incline of the occlusal plane in relation to the horizontal plane as it follows the teeth in the dental arch from the central incisors to the second molars, that may be required for accuracy in the making and fitting of artificial dentures.

In order that the useful advantages of this invention may be more readily understood, reference is made to the accompanying drawings, with the understanding that changes and modifications in the details of construction may be made within the scope of the appended claims, without departing from the spirit of the invention in its broader aspects.

In the accompanying drawings:

Figure 1 is a side elevation of a standard type of articulator, showing the improved dental template and its adjustable mounting positioned thereon;

Figure 2 is a graph, representing a cross-section of the dental arch, in the vertical transverse plane indicated by the median line ML on

Figure 1;

Figure 3 is a perspective view of the substantially wedge-shaped member for effecting adjustments of the template and its mounting;

Figure 4 is an enlarged, fragmentary, vertical, longitudinal section, through the articulator jaw and the template mounting and adjustable wedge assembly;

Figure 5 is a horizontal section, taken through the line 5—5 on Figure 4;

Figure 6 is a perspective view of the guide member and clamp assembly, with which a lock-screw of the articulator cooperates to secure the template, mounting and wedge assembly, in a position of adjustment on a supporting part of the articulator;

Figure 7 is a fragmentary, side elevation, of the articulator, showing a companion template, mounting, and wedge assembly, for setting up the upper artificial teeth, positioned on the base part of the articulator; and,

Figure 8 is a perspective view of a modified form of the template and mounting assembly.

Referring to the drawings, and more particularly to Figures 1 and 2, it is first to be noted that, in the art of artificial denture construction, the establishing of the horizontal plane HP is of paramount importance. This plane has two wings, one on each side of a central portion that is placed in the mouth between bite blocks (not shown), with the wings on each side parallel to a line drawn on the face from the upper margin of the external auditory meatus to the lowest part of the wing of the nose. The horizontal plane, when viewed from the front, should be parallel to a line passing through the pupils of the eyes. Most all makes of articulators have markings on the incisal pin and the condyle posts to facilitate the mounting of denture models on this plane.

In Figure 1, an occlusal curve OC, for the teeth, is shown in correct elevation relative to the horizontal plane HP as it follows the teeth in the arch from the central incisors to the second molars. As the teeth are progressively farther from the median line antero-posteriorly, the occlusal curve will be upward at the posterior end relatively to the horizontal plane. An occlusal plane OP, generally defined as a plane which passes between points representing one-half of the incisal over-bite and one-half of the cusp height of the last molars, is obtained from the occlusal curve OC in contact with the cusp tips of the lower incisors and the buccal cusp tips of the posterior teeth. This curve also contacts the sulci of the upper posterior teeth and the lingual surfaces of the incisors and, since the curve is common to the upper and lower teeth in centric relation, it thereby becomes the controlling factor in establishing the occlusal plane OP. Therefore, the normal plane of occlusion, as viewed from the side, is a straight line, tangent to this common occlusal curve. This plane OP also has application to either the upper or the lower arch and the normal upward

incline at the posterior end is about three to five degrees, relative to the horizontal plane HP.

In the mounting of models and the setting up of teeth, the size of the individual must be considered, e. g., the tall man can take a longer stride than a shorter one, hence, his walking pattern is the larger. This is true of the masticatory function. Therefore, in Figure 1, which shows a template 10, having the curvature OC of a sphere, mounted in the articulator and establishing the occlusal plane OP in relation to the horizontal plane HP, it is to be noted that the distance from the condyle elements C to the vertical center of the template and its mounting is to be adjusted to position the said center relative to the horizontal plane HP, in conformity with the size of the individual, thus permitting the setting of the teeth to the occlusal curve OC and the obtaining of a proper degree of incline of the occlusal plane OP, relative to the horizontal plane HP, that the operator may deem to be convenient; the changing of the occlusal curve being effected by a forward or backward adjustment of the template and mounting assembly relatively to that part of the articulator on which it is supported; the means to effect such adjustment to be presently described. The molars of a larger mouth will be farther from the median line ML (Figures 1 and 2) than those of the smaller mouth, as can be seen by comparing the tooth positions shown in the two figures. Therefore, to maintain the correct position of the occlusal plane OP, in relation to the horizontal plane HP, the occlusal curve must be elevated.

In carrying out the objects and purposes of my invention, I provide a mounting for the template 10, having the form of an open frame, which is comprised in a substantially wedge-shaped base 12 and front and rear standards 14 and 16, respectively, supporting the template in spaced relation with respect to the base; the rear standard 16 being substantially Y-shaped to have its angled arms connected with the template at opposite sides of its longitudinal center and of a cutout 10a, in the rear end portion thereof. The base 12 is longitudinally slotted, as at 12a, for its sliding adjustment on a guide element 18 and relatively to an adjustable wedge 22; the latter being correspondingly slotted, as at 22a (Figure 3), for like adjustment on the guide element 18.

As shown in Figure 1, the template and mounting assembly is inverted for its adjustable support from and lengthwise of the under side of the hinged jaw B, of the articulator, to which end, a clamp plate 20 is mounted on the under side of the guide element 18 and engages the lower side of the base 12, at opposite sides of the slot 12a, when the guide element 18 is engaged in the slots 12a and 22a, respectively, of the base 12 and the wedge 22. The guide element 18 is provided with a screw threaded axial bore 18a (Figure 6) for the engagement therewith of the usual model attaching lock-screw E (Figure 1), carried by the articulator jaw B, so that, when the lock-screw E is tightened, the base 12 and the wedge 22 will be clamped together, in their relatively adjusted positions between the under side of the articulator jaw and the upper side of the clamp plate 20. The guide element 18 and the clamp plate 20 are both rectangular in form, with the latter having a width equal to that of the base 12 and at least one side edge provided with a graduated scale 20b, for cooperation with a similar scale 22b, on the complementary side edge of the wedge 22 (Figures 1, 3, and 6), and an index mark 12b, on the corre-

sponding side edge of the base 12, which index mark 12b, together with a like index mark 10b, on the corresponding side edge of the template 10, defines the median line ML (Figures 1 and 2). The clamp plate 20 is provided with a slot 20a, in the side portion opposite from the scaled side portion thereof, which registers with a similar slot 22f, formed in the wedge 22, so that both slots are engaged by a guide element or screw 24, which is threaded upwardly through the base 12 (Figure 4), to allow relative adjustments of the base and the wedge, while, at the same time, coupling the clamp plate to the base.

The outer, i. e., inclined, face of the base 12 is formed with a groove 12c, opening outwardly through the rear end edge thereof from the slot 12a; the groove being narrower than the latter and adapted to register with a slot 22d, formed in the rearwardly directed end of the adjustable wedge 22, when the latter is operatively positioned on the base 12. The top side of the wedge 22 is also provided with a groove 22e, opening outwardly through its front end edge from the slot 22a and in alignment with the slot 22d. A slot 22g is formed in the bottom of the groove 22e, for the passage therethrough of a guide element or screw 26, which is threaded into the base 12 to couple the wedge thereto but, otherwise, allow for the relative adjustment of the base and wedge, the headed end of the guide element or screw engaging in the groove 22e, to that end. A guide element or pin 28 is carried by the articulator jaw B and engages in the slot 22d and the groove 12c, respectively of the wedge and base, to maintain the alignment of the wedge and base during relative movements of adjustment thereof. Thus, the template, the mounting, and the wedge, are assembled as a unit, for quick and easy attachment to and removal from the supporting part of the articulator, which is to be accomplished by merely manipulating one or the other of the lock-screws E and F relatively to the guide element 18, to tighten up on or free the clamp plate 20.

In the position of the template 10 (Figure 1), the occlusal curve OC is that of a more or less normal patient, but, in the case of a patient having an abnormal formation, in which the center of the sphere is located at the distal portion of the second molar, the template 10, to provide a proper occlusal curve, would have to be adjusted rearwardly on the articular jaw B and relatively to the median line ML, to effect the proper relation of the occlusal plane OP to the horizontal plane HP, i. e., the occlusal plane OP would be an incline anteriorly and a decline posteriorly, while, in the case of a patient where the center of the sphere is located in the region of the lower second bicuspid, the template 10 would be adjusted forwards, thereby lowering the central incisors and causing the posterior molars to be progressively higher, when the incline of the occlusal plane OP will be posteriorly in relation to the horizontal plane HP.

Inasmuch as the occlusal curve OC applies equally to the upper and lower teeth alike, when the teeth are disposed in centric relation, it is a matter of choice of the operator as to which type of template he may use, the convex type as shown in Figures 1, 4, and 5, or the concaved type as shown in Figure 7; it being possible to obtain the same results with either in establishing the occlusal plane OP in relation to the horizontal plane HP. However, if the concaved type, indicated at 10' (Figure 7), is employed, the adjustable mounting and wedge assembly, identical to that

as shown in Figures 1 and 4, is secured in position on the base A, of the articulator, by a second model attaching screw F, carried by the latter; the adjustment of the mounting and wedge being accomplished in the same manner, as in the first instance. Also, the same mounting and wedge assembly can be employed advantageously with a flat template, such as is indicated at 10", in Figure 8; it being here noted that some dentists set up teeth on a plane, in disregard of the occlusal curve or plane, and, consequently, encounter mechanical difficulties in setting up the teeth with a desired degree of correctness, since it is sometimes impossible to distinguish between the upper and lower levels. By the use of the graduated scales and index marks, it will be evident that, once a template has been adjusted to a required position, it may be removed and replaced in exactly at that position. Again, it will be equally evident that the template mounting and adjustable wedge assembly is capable of being attached to a conventional articulator without need for alteration, the usual model attaching lock-screws E and F being employed for the purpose. By providing the cutout in the rear central portion of the templates a manipulating space, i. e., opening, greatly facilitates accurate work performance.

What I claim is:

1. In the art of artificial denture construction, a template for use with dental articulators equipped with model attaching lock-screws in the base and jaw parts thereof, a mounting for said template and including an elongated base portion having a slot, a clamp means engageable with said mounting and one or the other of said lock-screws to secure the template in an adjusted position, and a guide element carried by said clamp means and engageable in said slot to maintain the alignment of said template and the mounting with respect to the supporting part of the articulator.

2. The invention as defined in claim 1, with said mounting having the form of spaced supports connecting the template with said base portion at opposite sides of the longitudinal centers thereof, said base portion having an outer inclined face, and a wedge-shaped member adapted to be interposed between said base portion and the opposed surface of the supporting part of the articulator, said member also having a slot adapted to be engaged by said guide element to allow for relative adjustment of said base portion and the member.

3. In the art of artificial dental construction, a template for use in dental articulators equipped with model attaching lock-screws in the base and jaw parts thereof, a mounting for said template including a base member having an inclined outer face and a slot disposed centrally of the same, a wedge member seated on said inclined face of the base member and having a centrally disposed slot in registry with the slot in said base member, means coupling said wedge member to said base member in a manner to allow relative adjustments between the same for the adjustment of said template to any degree of incline in relation to the horizontal plane as may be required for the setting up of teeth in conformity with the average occlusal curve for all sizes of individuals, a guide member engaged through the slots in said base and wedge members to maintain the members in alignment, and a clamp element carried by said guide member and engageable with said base member, said guide member being engageable with one of the said lock-screws to secure the template, mounting and wedge member assembly, in the required position of adjustment relatively to the supporting part of the articulator, said clamp element having a graduated scale thereon and said base member an index cooperative with said scale to indicate the exact position of adjustment of said template, whereby the assembly may be removed and thereafter accurately replaced in such previously adjusted position.

4. The invention as in claim 3, with said base member of wedge form corresponding to that of said wedge member and having its front and rear ends provided with angled portions forming standards rigidly connected with the like ends of said template, and said template being of a curved formation representative of a segment of a sphere.
